UNITED STATES PATENT OFFICE.

CHRISTOPHER A. SHEA, OF MILTON, AND JOHN J. O'LALOR, OF MEDFORD,
MASSACHUSETTS.

ELECTRICALLY-CONNECTED PRINTING-MACHINE.

SPECIFICATION forming part of Letters Patent No. 623,293, dated April 18, 1899.

Application filed April 20, 1896. Serial No. 588,283. (No model.)

To all whom it may concern:

Be it known that we, CHRISTOPHER A. SHEA, of Milton, in the county of Norfolk, and JOHN J. O'LALOR, of Medford, in the county of Middlesex, State of Massachusetts, citizens of the United States, have invented a new and Improved Electrically-Connected Printing-Machine, of which the following is a full, clear, and exact description, reference being had to the accompanying drawings, forming a part of this specification, in explaining its nature.

Our invention relates to improved apparatus for use with electrically-connected printing-machines whereby the depression of a key by the operator of the transmitting-machine will cause the corresponding key of the receiving-machine to be operated. The devices which have been in use heretofore for accomplishing this purpose have been objectionable for several reasons. Some of the systems require several line-wires and the initial expense is so great as to preclude their use. Others use only one wire; but these systems depend on the action of synchronous motors at each end of the line. When these motors get out of step, a misprint results and every letter subsequently struck is misprinted. In order to correct this, the machines have to be brought to unison and the motors thus brought back to synchronism. This is often a matter requiring some time, and until it is accomplished the machines are useless. By our invention we are enabled to do without the synchronous motors, and thus obviate the likelihood of misprinting.

An important feature of our invention is that all the machines in the line are automatically brought to unison after the printing of each letter. The operating parts of the machine start from the same position of rest or unison-point as each key is depressed, and after the key is released the arms are brought to that point again.

We have shown our invention as applied to the Hammond type-writer; but it may be used with any printing-machine which operates on a similar principle.

In the drawings, Figure 1 is a diagrammatic representation of our invention, showing a transmitting and a receiving type-writer connected by a line-wire. Only so much of the

type-writers is shown as is necessary to explain the operation of our invention. Fig. 2 is a view in section representing the carriage feed and return. Fig. 3 is a detail view to 55 which reference will be hereinafter made. Fig. 4 shows the manner in which the capital or figure key of the receiving-machine is operated.

Fig. 1 represents two Hammond type-writers connected by a single line-wire. The machines with our invention added are alike, so that either one may be used as a transmitter or receiver; but for convenience in description we have represented X as the transmitting-station and Y as the receiving-station.

P is a key fulcrumed at F, which when struck with the finger by the operator at station X raises a rod R, which protrudes through the hole h. At the same time the key raises 70 an arm A, which is fastened to the shaft S, to the other end of which is secured a driving-arm D, carrying at its end a fork E. When the driving-arm is moved forward by the raising of arm A, the fork engages with a pin p, 75 which is attached to the type-shuttle T, having on its periphery the type. This movement advances the type-shuttle until it strikes the shuttle-arm M, which, being movable, is carried along with it, the front end moving to 80 the right until it strikes the rod R, which has been raised by the back end of the key P. This stops the shuttle-arm and with it the type-shuttle and presents to the hammer H the letter "P." By this time the key P has 85 raised another arm N, which at its back carries a projection n. This projection moves downward when the arm N is raised and in doing so strikes the back end of the pawl n', forcing it down. The front end of the pawl 90 n' rises, engages, and moves the ratchet O', which rotates one step, being stopped after that by the front end of the pawl n', which engages with it on rising. The ratchet-wheel moves on the pawl n', the purpose of which 95 is to prevent by its engagement with the teeth of the ratchet the backward movement thereof. The rotation of the ratchet O' releases a spring which drives the hammer forward, printing the letter "P" on the paper. The 100 key P is then released by the operator and falls back to its normal position. The ham-

mer flies back, the spring s restores the arm A to its normal position, and the driving-arm D , the type-shuttle T , the shuttle-arm M , and the rod R are restored to their normal positions and all parts of the machine resume the positions shown in Fig. 1. When the next key is depressed, the same movements occur, and the letter corresponding to that key is printed on the paper. These movements belong to the Hammond type-writer and are only described in order to show how the electrical apparatus is adapted to them.

When the shuttle-arm M is moved by the driving-arm D over toward the rod that has been raised by the depression of the key, it moves over and makes contact with a commutator C , which is divided into segments, each successive segment being connected to an opposite polarity of current.

G G' are positive and negative dynamos furnishing the current. When the key P has been depressed by the operator, the shuttle-arm is moved over to the rod of that key and comes to a stop when it strikes it. If the key were the fifteenth key, the shuttle-arm would move over fourteen segments of the commutator and come to rest on the fifteenth, sending to the line and the station Y fifteen alternations of current. The line is connected from the shuttle-arm to the post a and thence to the two-point switch a' , which is turned to the left-hand contact at the transmitting-station X when it is desired to print to station Y , as shown in Fig. 1.

It will be noticed from the foregoing description that the shuttle-arm M returns to its original position or unison-point on the segment m of the commutator C after each key is released and starts from that point when the next key is depressed.

The current passes to the station Y by way of relays R' R^2 , and at station Y it flows around the armature A' of relay R^3 and then to earth. Relay R^3 is polarized, N S being a permanent magnet. The armature A' will therefore move up and down on its center b , the polarity of the first current governing the direction of the first movement. Attached to the armature A' are two arms x x' . Their normal position is between the teeth of the escapement-wheels E E' . These wheels are constructed in a peculiar way, as is better shown in Fig. 3. The ends of the arms x x' rest between the two wheels E E' . The first downward movement of either arm engages with a tooth of wheel E' . If the polarity of the first impulse from station X is a positive one, the shuttle-arm M moves to the right and the arm x moves downward. In doing so it strikes the tooth of wheel E' and turns the wheels and the shaft S' , which is fastened thereto, the distance of one tooth to the left. The next impulse, which will be a negative one, will move the arm x upward, which will strike the tooth above it and move the shaft the distance of one more tooth to the left, and so on. In the meantime the arm x' has been moving

in the opposite direction to the arm x and has encountered no teeth. Its first movement was upward and the next downward, and so on; but the wheels are so formed that the arm x' moves in open spaces during the succeeding alternations of current.

If the first current from station X be negative, there will be a reverse effect. The end of the armature A' to which the arm x' is fastened will be moved first. This will move the arm x' downward first, and it will engage with the tooth below and drive the wheels and the shaft S' the distance of one tooth to the right. The next impulse will send the arm upward, and it will strike another tooth and drive the shaft the distance of one more tooth to the right, and so on. In the meantime the arm x has been playing between blank spaces. By this arrangement of the teeth on the wheels the shaft will be driven in opposite directions by the two arms of the relay R^3 . The wheels E E' can be reversed in position, if desired, and the first upward movement of either arm may then be made to govern the direction of the shaft's motion. The first impulse from the commutator C at station X may be negative instead of positive by connecting the negative dynamo to the first segment instead of the positive one.

Attached to the shaft S' is the contact-arm M' . This moves with the shaft and moves over the segments of the commutator C' , to each segment of which is connected a solenoid O , having a movable core o and a fixed core o' . When the solenoid is energized by the local battery L , it pulls the movable core o down, and with it the key P , to which the movable core is attached. This of course has the same effect as striking the key with the finger, and it prints the letter on the paper of the machine in the same way. In order to release the key after the letter has been printed on the receiving-machine at station Y , the electromagnet M^2 is brought into action. When the key P has been pulled down by the solenoid O , the hammer is driven forward in order to print the letter on the paper. As it moves forward it closes the circuit of the electromagnet M^2 at contacts c c' , the former being fixed and the latter attached to the hammer.

The armature A^2 of the electromagnet M^2 is fastened to the shaft S' and turns with it, and when it turns it moves out of its normal position between the poles of the magnet M^2 . When the circuit of this magnet is closed, the magnetism generated at its poles will act upon the armature A^2 with such a force that it will pull it around, so that it will come back to its normal position between the poles of the magnet and be held there. The shaft S' will be turned at the same time, and its contact-arm M' will be brought to the segment m' . This segment is its position of rest or unison-point, and there is no solenoid connected with it. When the arm M' is returned to its unison-point, it is moved off the segment of the com-

mutator C', to which the solenoid is connected, and in moving off the circuit of the solenoid is broken. The movable core o' is no longer attracted into the solenoid and it flies up, allowing the key P to take its normal position.

It will be apparent from the foregoing description that at the same time that the shuttle or contact arm M of the transmitting-machine at station X is returned to the unison-point m by the mechanical devices of the Hammond machine the contact-arm M' of the receiving-machine at station Y is brought to its corresponding unison-point m' by the armature A² of the magnet M², as just described.

When the hammer H of the transmitting-machine at station X flies forward, it opens the line at contacts c² c³. This is done for the purpose of breaking the circuit, so that the armature A' of the relay R³ of the receiving-machine at station Y will come to rest between the two wheels E E' and allow them to be turned by the armature A² of the magnet M². If the line were not opened in that way, the arms of the armature A' would be held up or down into a tooth of the wheels E or E', and the shaft S' would be prevented from turning freely. The contact c³ is fixed and contact c² is attached to the hammer. After the letter has been struck on the transmitting-machine at station X the key is released by the finger and the shuttle-arm M falls back to its original position. In doing so it makes contact with the commutator C, and were the line closed it would send currents to station Y, thereby driving the escapement-wheels of the receiving instrument farther on; but as the line is open at the hammer these currents are not sent to station Y. The hammer H closes the circuit when it flies back. It returns to its normal position as soon as the shuttle-arm M does, and therefore the line is closed in time for the next letter to be printed.

Either machine can be used for office-work by simply turning the two-point switch s to the right. This leaves it in a position for receiving, as is shown at station Y in Fig. 1.

Fig. 2 illustrates the paper-carriage feed, release, and return.

S² is a shaft, on the back end of which is a collar, with a slot turned in it all the way around in order to allow the two prongs of a fork to clutch it, so that it can slide the shaft S² back and forth and yet allow it to be turned by the spring s'. The fork is securely attached to the rod R⁴, which extends under the machine and is connected to the crank R⁵, attached to the key K. When the key is depressed at the transmitting-machine at station X or pulled down by the electrical devices of the receiving-machine at station Y, the fork moves the shaft S². Upon this shaft is securely fastened the ratchet O², in the teeth of which the pawl n² engages to keep the spring s' from unwinding. A drum D² is loose upon the shaft S², and the ratchet O² is secured to this drum. The pawl n² only engages with the teeth of the ratchet when the

shaft and drum are pushed out. The drum D² is free to turn on the shaft S², but moves with it when it is pushed out. Firmly secured to the other end of the drum D² is the gear-wheel G², upon which the teeth of the carriage-rack K' ride. They also ride upon the gear-wheel G³, which is sleeved on the shaft S², so as not to move with it.

The spring s' is fastened on its end to the shaft S² and at the other end to the drum D². It has been wound up to the necessary tension, and in the tendency to unwind gives the drum D² a direction of rotation. This forces the carriage-rack and carriage in the same direction, and upon a stroke of the type-writer key it moves one definite distance. The carriage does not move until a key is struck, being held by a pawl against a tooth of the ratchet-wheel O', and as soon as a key is struck the pawl is moved away one tooth and then restored, moving one tooth ahead upon the pressure of the succeeding key. This is a feature of the mechanical type-writer and is not claimed as a part of our invention.

When the carriage is to be returned, the key K is depressed by the operator at station X and pulled down by the electrical devices at station Y. This pushes the rod R⁴ back and with it the shaft S². The drum D² and gear-wheel G² are thereby pulled completely out from under the rack K'. The rack then rests upon the gear-wheel G³ alone, the spring s² of which has been wound up by the forward movement of the carriage-rack and has acquired sufficient tension to turn the gear-wheel G³ in the opposite direction to that in which the spring s' turned the gear-wheel G². As the rack K' now rests upon the gear-wheel G³ only and as this gear is given a tendency to rotate by its spring s², the rack is forced along with it until it is returned to the starting-point. When this point is reached, the key is released, the shaft S² is restored, and the gear-wheel S² slips under the rack and is ready to move it forward again. The spring s' is very much more powerful than the spring s², which is just strong enough to return the carriage, the latter being very light and riding over rollers. When the drum is pulled out from under the rack K', the pawl n² engages with a tooth of the ratchet O², preventing the spring s' from unwinding. The pawl n² is always engaged in a tooth of the ratchet O².

The spring s' is wound to the requisite tension to force the carriage-rack K' along one step upon the pressure of each type-writer key. As the spring unwinds at that rate, it would very soon become run down. This is overcome by means of the electromagnet M⁴. After each key is struck the circuit of the electromagnet is closed at Z or any other suitable place and its armature A⁴ pulled upward. The end a⁴ of the armature fits into a tooth of the ratchet O², forcing it around and winding the spring s' one step. This happens with every letter, and the spring s' is thus kept at its initial tension.

Instead of the armature of the electromagnet winding up the spring s' it can be replaced by a lever attached to any of the movable arms, sufficient pressure being given the keys to move the lever with force enough to drive the ratchet O^2 one tooth for every tooth it loosens. The lever in that case would take the position now occupied by the armature of the magnet M^4 .

In Fig. 4 we have shown one method of holding down and locking the capital or figure key of the receiving-machine and also the method of releasing it. When the capital-key of the transmitting-machine at station X is depressed, it sends to the line a definite number of pulsations, according to its position. In this case it is the first key. Therefore it sends one impulse to the line. This moves this contact-arm M' of the receiving-machine at station Y onto the first contact c' of the commutator C' . The solenoid O^2 is thereby energized, and it pulls down its movable core o^2 and with it the capital or figure key K^2 . At the same time the stationary core O^3 of the solenoid becomes a magnet and attracts the armature A^5 to it. As the armature moves toward the magnet it strikes the rod R^6 and forces its upper end against the notch l^7 in the latch L^2 , which is pivoted at l^2 , and drives it forward, when it engages with the collar C^2 on the movable core o^2 and holds it down. Just at this time the armature A^5 has closed the circuit of the electromagnet M^2 at y . The magnet attracts its armature A^2 and restores the contact-arm M' to the position of rest on the segment m' . The circuit of the solenoid O^2 is thereby broken and the armature A^5 falls back to its original position. The movable core o^2 will tend to rise, but will be prevented from doing so by the latch L^2 , which holds down its collar C^2 .

When the figure or capital key is released by the operator at station X, one impulse will be sent to the line, the contact-arm M' of the receiving-machine at station Y will be moved to the segment c' , and the circuit of the solenoid O^2 will again be closed. The solenoid will be energized and will attract the armature A^5 , as before described. This motion of the armature will operate the rod R^6 and the upper end of the rod will engage with the notch l^7 of the latch L^2 , which was driven forward, as above described. The shape of the latch is such that the engagement of the rod R^6 with the latch l^7 will drive it back to the position shown in Fig. 4. The collar C^2 will then be free from the latch and the movable core o^2 will rise when the armature A^2 of the segment M^2 has broken the circuit of the solenoid O^2 , as before described.

The operation of our invention is as follows: The operator at station X depresses the key P . This may be the fifteenth or any other key, and assuming that it is the fifteenth key the shuttle-arm M will be moved around to the fifteenth rod R , which has been raised, and will stop there, as before described. In moving over to

the fifteenth rod the arm M passes over fourteen contacts of the commutator C , one for each key, and comes to rest on the fifteenth. 70 This sends fifteen currents to the line and moves the armature A' of relay R^3 of the receiving instrument at station Y fifteen times. The armature A' by means of its arms moves the shaft S' and the contact-arm M' in the manner already described to the fifteenth segment of the commutator C' , where the contact-arm comes to rest. The solenoid O is thereby energized and pulls down the key P , which corresponds to the one depressed by the operator 80 at station X. When the hammer H of the receiving-machine at station Y flies forward, it closes the circuit of the magnet M^2 , which restores the contact-arm M' to the unison-point on the segment m' by means of its armature 85 A^2 , as has been also described. At the same time the shuttle-arm M of the transmitting mechanism at station X is returned to the unison-point on the segment m mechanically on the release of the key P . The two arms 90 M M' move in step with each other and each is restored to its original position or unison-point after the printing of every letter, and should one letter for any reason be misprinted at station Y the next one will be correctly 95 printed, as the contact-arm M' will have been restored to the unison-point after the misprinting of the letter and will therefore be in a position to be correctly operated by the depression of the next key. The contact-arm M' of the receiving-machine at station Y moves so quickly over the contacts of the commutator C that the solenoids are not energized until it comes to rest.

If the line-wire should open or "ground" 105 or get crossed with another, so that station Y will not get the currents from station X, the transmitting-machine at station X is locked automatically, so that it cannot be operated. This is accomplished by means of the relays 110 R' R^2 . The currents from the transmitting-machine at station X in passing to the receiving-machine at station Y flow through these relays. The spring r' of relay R' is sufficiently strong to overcome the magnetism 115 of its core, and it therefore keeps the armature up at the top stop. The spring of relay R^2 , however, is weaker, and the currents flowing through that relay pull the armature down and keep it on the lower stop. The electromagnet M^3 is therefore kept on open circuit. If the line-circuit should open, the current 120 will not circulate around the relay R^2 , and the spring, having no magnetism to overcome, will then pull the armature to the upper contact. 125 In doing this it will close the circuit of the electromagnet M^3 , which pulls its armature A^3 forward and directly under the pawl n' , holding it firmly, and thereby preventing the ratchet O' from moving and locking the machine. Should the line become "grounded" 130 or crossed with another wire, the excess of current flowing around the cores of the relay R' will create a greater amount of magnetism

in its cores, and this increase will overcome the force of the spring r' and pull the armature down to the lower contact, closing the circuit of the magnet M^3 and locking the type-writer. The armature A^3 of the magnet M^3 , which is upon open circuit, is free from the pawl n' when the line-wire is in working condition, and it does not interfere with the operation of the machine. This magnet, with its armature, can be placed at any other part of the machine where it will prevent its operation by holding the moving parts of the machine firmly.

When the shuttle-arm M of the transmitting-machine at station X is resting in its normal position on the segment m , there is no current flowing to the line. This would cause the relay R^2 to open and lock the machine but for the local circuit which is kept closed through its coils. This circuit can be traced from the shuttle-arm, wire W , local battery L' , around relay R^2 , to the shuttle-arm by wire W' . When the shuttle-arm moves off this contact, it throws the relay R^2 into the line-circuit.

Any type-writer operated upon a mechanical principle similar to that of the Hammond machine can be equipped with similar electrical apparatus, and any printing-machine that has a "type-shuttle," "type-wheel," "type-cylinder," or which has all its letters on one or two pieces of mechanism which turn or move one definite distance farther with the depression of each succeeding key, can be operated upon the electrical principle herein described. This can be done by alternating "make" and "break" or "increase" and "decrease" currents. Upon the printing of each letter the type wheels or cylinders are mechanically brought to their original position. This principle can be adapted to any of the type-bar machines should any piece of their mechanism move one definite distance farther with the depression of each succeeding key, or such a piece of mechanism could be attached to them.

Having thus fully described our invention, we claim and desire to secure by Letters Patent of the United States—

1. The combination in a system of electrically-connected printing-machines of a mechanical type-writer containing a mechanism which is moved from a determinate position one definite distance farther by the depression of each succeeding key of the machine, and which is restored to a determinate position upon the release of the key, of a series of contacts over and upon which the mechanism passes, a source of electricity and a line-wire, substantially as described.

2. The combination in a system of electrically-connected printing-machines of a mechanical type-writer containing a mechanism which is moved from a determinate position one definite distance farther by the depression of each succeeding key of the machine, and which is restored to a determinate posi-

tion upon the release of the key, a commutator over and in contact with which the movable mechanism passes, a source of electricity 7c and a line-wire, substantially as described.

3. The combination in a system of electrically-connected printing-machines of a mechanical type-writer containing a mechanism which is moved from a determinate position 75 one definite distance farther by the depression of each succeeding key of the machine, and which is restored to a determinate position upon the release of the key, a series of contacts by means of which pulsations of electricity are sent to the line and receiving instrument by the movement of the movable mechanism, and means for preventing further operation of the receiving instrument when the movable mechanism is being restored to its determinate position, as and for the purposes described.

4. The combination in a system of electrically-connected printing-machines of a source of electricity, a transmitting mechanism having a commutator and a contact-arm adapted to be moved one definite distance farther by the depression of each succeeding key of the machine and brought to its initial position on the release of the key, a receiving 95 mechanism having a commutator and a contact-arm adapted to be moved by one or more electromagnets in unison with the arm of the transmitting-machine and mechanism to automatically bring the contact-arm to its initial 100 position in unison with the transmitting contact-arm after the printing of each letter, as and for the purposes described.

5. In a system of communication by means of printing-machines connected by a single 105 line-wire, a receiving printing-machine, a contact-arm, one or more toothed wheels to move the contact-arm, one or more electromagnets to operate the wheels and mechanism to automatically restore the contact-arm 110 to its initial position instantly upon the printing of each letter and before the next is struck, in combination with a transmitting-machine, a commutator and a source of electricity, a contact-arm adapted to be moved one definite 115 distance farther by the depression of each succeeding key of the machine and restored to its initial position upon the release of the key, both contact-arms moving in unison, substantially as described.

6. In a system of communication by means of printing-machines connected by a single line-wire, a receiving printing-machine, a contact-arm, one or more toothed wheels to move the contact-arm, one or more electromagnets to operate the wheels and mechanism to automatically restore the contact-arm to its initial position instantly upon the printing of each letter and before the next letter is struck, as and for the purposes described. 125

7. In a system of communication by means of printing-machines connected by a single line-wire, a receiving printing-machine having a commutator, a contact-arm adapted to

be moved a step farther by each succeeding impulse from the transmitter and to be automatically brought to its initial position by means independent of the transmitter in-
stantly after the printing of each character and before the next letter is struck, as and for the purposes described.

8. In a system of communication by printing-machines connected by one or more wires, a receiving-machine, a contact mechanism adapted to be moved by one or more toothed wheels, one or more electromagnets to operate the wheels and means for automatically bringing the contact mechanism to a determinate position by the action of the printing of each character, as and for the purposes described.

9. The combination in a system of electrically-connected printing-machines of a paper-carriage having a rack, a spring for moving the carriage one step with the depression of each key, a drum, a gear, means for winding the spring with each step it loses, mechanism for moving the drum from under the rack, a ratchet-wheel and pawl to prevent unwinding of the spring and a spring for returning the carriage wound by the forward movement thereof, substantially as and for the purposes described.

10. The combination in a system of electrically-connected printing-machines of the paper-carriage, the shaft S², the rod R⁴, the drum D², the spring s', the ratchet O², the spring s², the gear G³, the electromagnet M⁴ with its armature A⁴ and the pawls n², n³, substantially as described.

11. In a system of communication by means of printing-machines connected by a single line-wire, a receiving printing-machine, two wheels each with oppositely-inclined teeth

adapted to move a contact-arm in opposite directions, one or more electromagnets to move the wheels, and mechanism to automatically restore the contact-arm to a determinate position upon the printing of each character, as and for the purposes described.

12. The combination in a system of electrically-connected printing-machines of the polarized relay R³, the armature A' having the arms x, x', the wheels E, E', the commutator C', the contact-arm M', solenoids electrically connected to the segments of the commutator, the electromagnet M² with its armature A², as and for the purposes described.

13. In a system of communication by means of printing-machines connected by a single line-wire, a transmitting-machine, a contact-arm connected to the line-wire and adapted to be moved in opposite directions from a given position one definite distance farther by the depression of each succeeding key of the machine, a commutator over which the contact-arm moves, opposite electrical polarities connected to the first and to the succeeding segments of the commutator on each side of a given position and mechanism to automatically restore the contact-arm to the given position upon the release of the key, as and for the purposes described.

14. The combination in a system of electrically-connected printing-machines of the capital-key K², the solenoid O² having the movable core o², the armature A², the rod R⁶, the latch L² and the collar C², as and for the purposes described.
